UNITED STATES PATENT OFFICE.

WILLIAM H. COOLEY, OF BROCKPORT, NEW YORK.

MACHINE FOR EXPANDING SHEET METAL.

No. 909,065.

Specification of Letters Patent.

Patented Jan. 5, 1909.

Application filed September 8, 1908. Serial No. 451,999.

To all whom it may concern:

Be it known that I, WILLIAM H. COOLEY, a citizen of the United States, and a resident of Brockport, in the county of Monroe and State of New York, have invented a new and Improved Machine for Expanding Sheet Metal, of which the following is a specification.

This invention relates to means for expanding metal after it has been properly cut and corrugated, as will be explained. In order that the cut metal may be engaged at the keys or bonds and such keys or bonds drawn in straight lines, after there has been formed in the metal alternating and overlapping rows of cuts in substantially the usual way, it may be corrugated in a direction transverse to the direction of the cuts in such a way that alternate rows of bonds or keys are pressed in opposite directions, and I prefer that the metal be so corrugated that the corrugations will conform substantially to the contour of a series of dividing bars arranged transversely of the direction of the cuts and between two such transversely arranged adjacent series of meshes in the expanded metal. When thus corrugated, it is necessary only to bend every other row of bars in a direction opposite to that in which they extend in the corrugated sheet, while every intermediate row of bars is similarly drawn along that distance represented by the space between transversely extending adjacent rows of keys or bonds in the expanded metal.

In accordance with my present invention, I provide a series of continuously traveling fingers adapted to engage such a cut and corrugated sheet at the keys or bonds and draw such keys or bonds along in straight lines. For engaging and drawing the keys in this way, I make use of continuously traveling members having thereon projections adapted to engage the cut and corrugated metal at such bonds or keys. Such projections may be carried preferably by any suitable endless members operably supported on suitable rotatable elements, or such projections may obviously be arranged upon a suitable cylinder. In the accompanying drawings I have shown the latter arrangement. In expanding the metal in this way, it is necessary to engage only every other row of keys or bonds, that is, the cut and corrugated

metal may be engaged only at the keys in every other corrugation. The metal as it is expanded is drawn preferably in a plane substantially transverse to the plane of the unexpanded metal and the unexpanded metal is fed towards the expanding mechanism in such a way as to permit of the metal being readily engaged by such expanding mechanism.

The accompanying drawings show only such parts of an expanding mechanism embodying my invention as are necessary to illustrate the same. Such drawings are as follows:—

Figure 1 is a front elevation of a part of the machine, while Fig. 2 shows that part of the machine seen in Fig. 1 as viewed from the right, the plane of the section of Fig. 2 being substantially that of the right hand edge of Fig. 1. Fig. 3 is a top or plan view of part of the table and guiding mechanism for the corrugated and the expanded metal. Fig. 4 is an enlarged sectional view of a part of the machine, the plane of the section being substantially the same as that of Fig. 2. Fig. 5 shows a portion of a sheet of the cut and corrugated metal as prepared for expansion by means of my machine.

Similar letters refer to similar parts throughout the several views.

Referring to the drawings,—a machine embodying my invention may have side frame pieces A between which are bolted the plates T, P, and P¹, as well as also the support and guideway for the metal before it is expanded, the construction of which will be described later. At the top of each side member A are located bearings for a main shaft S having secured thereon the cylindrical member B carrying radially projecting teeth b. This cylinder B extends between the side members A of the frame, while outside of the side members A and on the left hand end of this shaft S, as seen in Fig. 1, is secured a spur gear G. On the front side of the frame pieces A are secured bearings for a shaft s, on the left hand end of which is secured the spur gear g meshing with the gear G. On this shaft s and just within the frame pieces A there are secured two wheels C having studs c projecting from the inner faces thereof and towards the center of the machine, only one of such wheels being seen in Figs. 1 and 2, together with their coöperat-

ing parts, all of such parts, however, are duplicated at the other end of the machine and are not shown.

Upon studs e secured in the ears or lugs 5 a^1 formed on the frame pieces A are pivotally secured the levers E, the upper ends of which are adapted to be engaged by the pins c on the wheels C. The other ends of these levers E engage between studs n and n^1 secured 10 in the upper ends of the rack feed bars R having ratchet teeth formed on their rear edges, being the edges seen to the right in Fig. 2. These rack bars R are supported upon studs s^1 engaging through slots r therefor in such bars R and such studs s^1 are rigidly secured in the cross pieces a forming 15 parts of the outside frame members A. Similar or other suitable guiding and supporting mechanism may be provided for the lower ends of the bars R. To these cross 20 pieces a there is secured the upper end of the rear and fixed portion D of the guiding frame for the cut and corrugated metal. The cut and corrugated metal, as seen at m , is held 25 between the plate D and the plate D^1 pivotally secured thereto at its lower end. On the upper end of this plate D^1 is seen a cross bar d^1 having on its ends pivotally secured latches h , as seen in Figs. 1, 2, 3 and 4, 30 adapted to engage suitable studs h^1 , projecting from the bar d on the front side of the member D at its upper end, to hold the plate D^1 in the position indicated in full lines in Fig. 2, being its operative position, and from 35 which position it may be swung to the position indicated in dotted lines at D^2 for the purpose of inserting a sheet of the corrugated metal m to be expanded. The plates D and D^1 extend downwardly to a sufficient 40 distance to receive the largest sheet of metal to be expanded by the machine, and this may vary according to circumstances.

Working freely up and down between the members D and D^1 is seen a bar V having 45 ears or lugs v projecting to the left therefrom and through slots o therefor in the plate D, as seen in Fig. 2. On the ears v are pivotally supported the latches v^1 actuated by means of the springs v^2 to hold them in engagement with the teeth on the rack bars R.

Near the upper end of the member D are provided ears u forming bearings for rollers U, over which pass the cords w secured to the weights W and to the guide bar V in such a way 55 that the weights W tend to raise the guide bar V to draw and hold the metal upwardly. Such weights W need not be, however, sufficient to positively feed the metal upwards, although they may be if so desired. They 60 should be of sufficient weight, however, to positively hold the metal at any time to the position to which it has been fed by the positively operating feeding mechanism. Of these rack bars R and their coöperating and 65 connecting parts there are two, only one of

them being seen in Figs. 1 and 2. There are likewise two weights W and connecting cords w working over pulleys U, only one of such duplicate parts being seen in Figs. 1 and 2.

The plate P^1 secured between the side 70 members A constitutes a bed upon which the expanded metal m^1 is forced to the right, as seen in Figs. 2, 3 and 4, such metal m^1 being forced underneath the plate P having fingers p thereon extending to the left, as seen in 75 Figs. 2, 3 and 4 and to the front of the machine underneath the cylinder B and between the rows of teeth b thereon in such a way that the expanded metal is caused to engage under such teeth p as it is forced to the right 80 by such teeth b engaging the same at points denominated the keys or bonds and successively at those rows of such keys or bonds seen to the right in Figs. 2, 3 and 4 and against the member D^1 . The plate T also 85 has fingers extending to the right in such figures, or to the rear of the machine, underneath the cylinder B and between the rows of teeth thereon in such a way as to constitute limiting stops against the under sides of 90 which the upper edge of the corrugated metal is fed, such teeth t engaging over the metal at that row of corrugations coming against the plate D in the supporting mechanism 95 for the cut and corrugated metal.

In operating my machine, the plate D^1 is swung to the position indicated in dotted lines at D^2 and the guide plate V lowered sufficiently to permit of the insertion of the sheet of metal m above the same and underneath the fingers t , then the door D is swung to the position indicated in full lines in Fig. 2 and locked in that position by means of the latches h and the machine being started, the metal m is fed upwardly against the under 100 sides of the fingers t engaging those rows of keys coming against the plate D, while those rows of keys coming against the plate D^1 are engaged by the teeth b , as indicated in Figs. 1, 2, 3 and 4 and drawn to the right in expanding the metal. As the metal is drawn to the right, the uppermost row of keys engaging under the teeth t being drawn away from under such teeth t , the metal is fed upwardly by means of either the weights W, if 110 sufficient to force the metal upwardly, but preferably by means of the feeding mechanism already described, comprising the rack bars R and the means for actuating the same and the spring actuated pawls v^1 carried by 115 the guide plate V. It will be noticed that the levers E have a small amount of free motion between the studs n and n^1 on the upper ends of the rack bars R, in order that the uppermost row of keys engaging under the 120 teeth t may be drawn to the right and away from under such teeth, while the right hand ends of the levers E pass from the position indicated in Fig. 2 into engagement with the upper studs n , after which the rack bars R 125 130

are drawn upwardly a distance equaling the space between the teeth on the right hand edges thereof, the parts being so adjusted angularly as to result in the sequence of 5 operations just above described.

It will of course be at once understood that instead of the arrangement shown in the drawings, the cut and corrugated metal may be fed either upwardly or downwardly to the 10 expanding mechanism and the expansion may be effected by drawing the metal in a horizontal direction if so desired, the action, however, being the same in either case and as already described.

15 What I claim is:—

1. In a machine for the purpose described, means for supporting a sheet of cut and corrugated metal; means for successively engaging the sheet at series of keys arranged 20 transversely of the corrugations therein and forcing such keys in straight lines in a plane substantially transverse to the original plane of the sheet to be expanded away from the next succeeding series of keys engaged thereby substantially without stretching or cutting the metal, the distance which such successively engaged series of keys are to be spaced apart in the expanded metal and means for advancing such sheet transversely 25 of the direction of the cuts at successive intervals, distances equaling the lengths of the portions of such sheet withdrawn therefrom at correspondingly successive steps in the expanding operation.

35 2. In a machine for the purpose described, means for supporting a sheet of cut and corrugated metal; means for successively engaging the sheet at series of keys arranged transversely of the corrugations therein and 40 for forcing each such series of keys in straight lines away from the next succeeding series of keys engaged thereby substantially without stretching or cutting the metal the distance which such two successively engaged series 45 of keys are to be spaced apart in the expanded metal and means for advancing such sheet transversely of the direction of the cuts at successive intervals distances equaling the lengths of the portions of such sheet withdrawn therefrom at correspondingly successive steps in the expanding operation.

50 3. In a machine for the purpose described, means for supporting a sheet of cut and corrugated metal; means for successively engaging the sheet at series of points arranged transversely of the corrugations therein and forcing such points in straight lines in a plane substantially transverse to the original plane of the sheet to be expanded away from the 55 next succeeding series of points engaged thereby substantially without stretching or cutting the metal the distance which such two successive series of points engaged thereby are to be spaced apart in the expanded 60 metal and means for advancing such sheet

transversely of the direction of the cuts at successive intervals, distances equaling the lengths of the portions of such sheet withdrawn therefrom at correspondingly successive steps in the expanding operation. 70

4. In a machine for the purpose described, means for supporting a sheet of the cut and corrugated metal; means for successively engaging the sheet at series of points arranged transversely of the corrugations therein and 75 forcing such points in straight lines away from the next succeeding series of points engaged thereby substantially without stretching or cutting the metal the distance which such two successive series of points engaged 80 thereby are to be spaced apart in the expanded metal and means for advancing such sheet transversely of the direction of the cuts at successive intervals distances equaling the lengths of the portions of such sheet 85 withdrawn therefrom at correspondingly successive steps in the expanding operation.

5. In a machine for the purpose described, means for supporting a sheet of cut and corrugated metal; means for successively engaging the sheet at series of keys arranged 90 transversely of the corrugations therein and forcing such keys in straight lines in a plane substantially transverse to the original plane of the sheet to be expanded away from the 95 next succeeding series of keys engaged thereby the distance permitted by such corrugations substantially without stretching or cutting the metal and means for advancing such sheet transversely of the direction of the 100 cuts at successive intervals, distances equaling the lengths of the portions of such sheet withdrawn therefrom at correspondingly successive steps in the expanding operation.

6. In a machine for the purpose described, 105 means for supporting a sheet of cut and corrugated metal; means for successively engaging the sheet at series of keys arranged transversely of the corrugations therein and for forcing each such series of keys in straight 110 lines away from the next succeeding series of keys engaged thereby the distance permitted by such corrugations substantially without stretching or cutting the metal and means for advancing such sheet transversely of the direction of the cuts at successive intervals distances equaling the lengths of the portions of such sheet withdrawn therefrom at correspondingly successive steps in the expanding operation. 115

7. In a machine for the purpose described, means for supporting a sheet of cut and corrugated metal; means for successively engaging the sheet at series of points arranged transversely of the corrugations therein and 120 forcing such points in straight lines in a plane substantially transverse to the original plane of the sheet to be expanded away from the next succeeding series of points engaged thereby the distance permitted by such cor- 130

rugations substantially without stretching or cutting the metal and means for advancing such sheet transversely of the direction of the cuts at successive intervals distances equaling the lengths of the portions of such sheet withdrawn therefrom at correspondingly successive steps in the expanding operation.

8. In a machine for the purpose described, means for supporting a sheet of cut and corrugated metal; means for successively engaging the sheet at series of points arranged transversely of the corrugations therein and forcing such points in straight lines away from the next succeeding series of points engaged thereby the distance permitted by such corrugations substantially without stretching or cutting the metal and means for advancing such sheet transversely of the direction of the cuts at successive intervals distances equaling the lengths of the portions of such sheet withdrawn therefrom at correspondingly successive steps in the expanding operation.

9. In a machine for the purpose described, means for supporting a sheet of the cut and corrugated metal having corrugations therein extending transversely of the series of keys and corresponding in contour substantially to the contours of any two bars on the same side of a mesh with the connecting key between them in the expanded metal; and means for engaging the corrugated sheet and bending every other transversely extending row of bars in substantially the opposite di-

rection from that in which they lie in the 35 corrugated sheet.

10. In a machine for the purpose described, means for supporting a sheet of cut and corrugated metal and means for engaging the sheet and forcing or drawing points correspondingly located on opposite sides of the cuts relatively apart substantially without stretching or cutting the metal in planes perpendicular to the original direction of the cuts and parallel to each other. 40 45

11. In a machine for the purpose described, means for supporting a sheet of cut and corrugated metal and means for engaging the sheet and forcing or drawing points correspondingly located on opposite sides of the cuts relatively apart substantially without stretching or cutting the metal in substantially straight lines in planes perpendicular to the original direction of the cuts. 50

12. In a machine for the purpose described, means for supporting a sheet of cut and corrugated metal and means for forcing or drawing points correspondingly located on opposite sides of the cuts relatively apart substantially without stretching or cutting the metal in substantially straight lines in planes perpendicular to the original direction of the cuts and parallel to each other. 55 60
